UNITED STATES PATENT OFFICE.

JOHN J. HAGGERTY AND ERNEST D. VAN WIE, OF ALBANY, NEW YORK.

LINE-SPACE FOLIO ATTACHMENT FOR TYPE-WRITERS.

1,266,796.

Specification of Letters Patent. Patented May 21, 1918.

Application filed March 9, 1916. Serial No. 83,032.

To all whom it may concern:

Be it known that we, JOHN J. HAGGERTY and ERNEST D. VAN WIE, citizens of the United States, whose residence is Albany, county of Albany, and State of New York, have invented certain new and useful Improvements in Line-Space Folio Attachments for Type-Writers; and they do hereby declare the following to be a full, clear, and 10 exact description of the invention, such as will enable others skilled in the art to which it appertains to make and use the same.

This invention relates to a line space indicator for typewriters, and has for its object to provide a device of this character which will indicate when a predetermined number of lines has been completed since the previous operation of the indicator.

In various classes of typewriter work it is 20 desirable to place along the margin of the sheet, numbers to indicate the line which would complete a folio of the typewritten matter. Typewritten matter usually runs ten lines to the folio, and in order for the 25 operator to put the line numbers opposite every tenth line he must keep account of the lines as they are written in order to shift the carriage to bring the space in the margin opposite the printing point before the 30 commencement of the tenth line.

By our invention we provide an indicator which operates to sound a signal when the carriage is returned after the desired number of lines have been written so that the 35 operator may write the line number at the beginning of the next line without having to keep in mind the number of lines written.

A further object of the invention is to provide an attachment of this character in 40 which the signal is operated at the beginning of the shifting movement of the carriage so that the operator may press the marginal release key before the movement of the carriage is completed to allow the extended movement for printing the line number.

A further object of the invention is to provide a device of the class described which may be applied to existing typewriters without 50 change in the typewriter design, by the mere substitution of a single part on which the attachment is assembled.

A further object of the invention is to provide a device of the class described which 55 may, with little change in the design, be

adapted to all standard makes of typewriters.

A further object of the invention is to provide an attachment of the class described which will operate to sound the signal after a predetermined number of lines have been written, regardless of whether the typewriter be set for the usual double space or for the single space or for triple space.

A further object of the invention is to provide an attachment for the purpose described which may be readily altered to change the number of lines between the successive operations of the signal.

With the above objects in view, our invention consists in the construction shown in the accompanying drawings and herein-after described, in which drawings we have shown our attachment as applied to an Underwood typewriter known as the "Underwood No. 5."

In the said drawings:

Figure 1 shows a side elevation of a portion of the carriage of the aforementioned Underwood typewriter with our attachment in place thereon;

Fig. 2 is a side elevation with the attachment removed from the machine, but showing the line space plunger and the cover plate;

Fig. 3 is a plan view of the attachment shown in Fig. 2;

Figs. 4 and 5 are sectional views on the correspondingly numbered lines of Fig. 2;

Figs. 6 and 7 are detail views of parts of the apparatus.

Referring to the drawings, and particularly to Fig. 1, 1 indicates the sliding carriage of a typewriter which carries the platen roller and the mechanism for intermittently rotating the platen to bring the paper into position for the successive lines. In the machine of the type described and in most other standard machines, the rotation of the platen is effected by means of a lever shown at 2, which also is used to shift the carriage to the right for the commencement of a new line. The lever is pivoted to the carriage for movement in a horizontal plane and is provided with an offset or shoulder 3 which engages the end of plunger 4 mounted for sliding movement on the carriage frame at right angles to the line of movement of the carriage. The plunger 4 carries a pawl for en-

gagement with the ratchet on the end of the platen and adjacent the plunger is a set 5 which engages under the pawl to determine which tooth of the ratchet is engaged by the plunger to thereby vary the extent of movement of the platen roller and the distance between the lines.

The movement of the plunger is the same for each operation of the carriage effected 10 through the lever 2, the set 5 merely determining the portion of the stroke of the plunger which is effective in turning the platen.

Our attachment is designed to be operated at the beginning of the return movement of 15 the carriage by the movement of this plunger and we have designed the attachment so as to be supported on the cover plate 6 which covers the end of the carriage in the manner shown in Fig. 1. Our attachment comprises 20 a bell or gong 7 which is supported at the lower rear edge of the cover plate 6 on a stud 8 projecting from the cover plate. Attached to the stud 8 within the gong is the striker 10 comprising the ball 9 on a spring 25 wire arm bent to maintain the ball just out of engagement with the inner edge of the gong. The stud 8 is formed with a reduced portion adjacent the face of the cover plate 6 to provide a bearing for a ratchet wheel 12 30 here shown as provided with ten teeth. The ratchet wheel is designed to be actuated by the reciprocation of the plunger 4 so that on each reciprocation of the plunger it will be advanced the distance of one tooth to thereby 35 complete a single revolution on ten movements of the plunger. The ratchet wheel is operated by a pawl 13 pivoted to the end of the bar 14 mounted for sliding movement in a guide slot 15 cut in the side face of the 40 cover plate at a point adjacent the end of the plunger 4 which extends beyond the pawl for turning the platen in order to provide an attachment for the return spring 16. The end of the plunger 4 is provided with a 45 pin to which the spring 16 is directly attached in the machine before our attachment is applied.

To this pin, indicated at 17, is attached a collar 18 having a circumferential groove 50 for receiving the end of the spring which previously fitted over the pin. The collar 18 is designed to slide in the groove of the cover plate as shown, and to its outer end is rigidly attached the bar 14 by means of a screw 19 and lug 21 which engages a slot in 55 the end face of the collar.

For operating the striker of the gong the ratchet 12 is provided with a pin 20 set in the outer face of one of its teeth in position 60 to engage the striker to force it back against the tension of the spring so that when released the striker will hit the edge of the gong. The position of the striker relative to the movement of the ratchet is so determined 65 that the pin will engage and release the

striker during a single movement of the ratchet wheel.

For preventing the back movement of the ratchet 12 upon the return of the pawl we may provide a small ratchet 22 on the face 70 of the larger ratchet, which ratchet is engaged by a spring pawl 23 to prevent the reverse rotation of the larger ratchet.

In operating a machine provided with our attachment the paper is placed in the machine and the platen turned by operating the handle 2 until the gong strikes. If the paper is not sufficiently advanced in the machine to begin the writing, the platen is further advanced by means of the knobs at the 80 ends of the platen so that the ratchet 12 will be left in position with the pin 20 immediately in advance of the striker. When the desired point on the page is reached for beginning the article, the writing is commenced, the rotation of the platen for the successive lines being thereafter effected by the lever in the usual manner. For each operation of the lever 2 the ratchet will be advanced a distance of one tooth, and after 10 ten lines have been written the pin 20 will at the beginning of the next return movement of the carriage again operate the striker indicating to the operator as he begins to shift the carriage that a folio or line number 90 is to be written before the matter forming a new line is commenced. He may then, with his other hand, press the marginal release key to effect movement of the platen beyond the stop set to determine the beginning of the line so that the continued movement of the carriage will bring the paper in position for the folio number.

If it is desired to number the lines at different intervals than every ten lines, the 105 ratchet may be provided with a greater or less number of teeth, the ratchet or pawl being shifted so that the effective stroke of the pawl shall be sufficient always to advance the ratchet through the space of one 110 tooth.

In applying our attachment to machines already in use we may provide a cover plate with the holes and slot for supporting the parts of the attachment provided in it so 115 that the attachment may be applied to the machine by merely removing the old cover plate and putting on the new plate and connecting the collar 18 to the pin 17 in the manner described. To effect the connection 120 of the attachment to the machine in this manner requires merely a screwdriver and no special mechanical skill so that the attachment may be applied by the typist without assistance and in a few moments' time.

In providing attachments for machines of makes other than that illustrated the support for the parts will have to be modified in various ways to correspond with the design of the particular machine carriage to 130

which the attachment is to be applied, also the parts for connection with the line space plunger or lever will be designed for cooperation with that part of the particular machine. It is to be understood that such changes and such other variations of the portions and arrangement of the parts as fall within the scope of the appended claims, may be made without departing from the 10 spirit of the invention.

Our improved attachment is located to the rear of the machine out of the way of the hands of the operator and adds but little to the weight of the machine, and nothing to 15 the bulk, as it does not project beyond the other projecting portions of the carriage.

We claim:

1. An attachment for typewriters having a reciprocating member for effecting the rotation of the platen and the return of the carriage after each line of writing, said attachment comprising a signal, a ratchet for periodically operating said signal upon continued rotation of the ratchet in one direction, a pawl for actuating the ratchet wheel, said pawl being connected to said reciprocating member to advance the ratchet wheel a predetermined amount upon each reciprocation of said member.
2. An attachment for connection to the carriages of typewriters comprising a bell, a ratchet wheel, means operated by the ratchet wheel for sounding the bell successively at uniform intervals upon the continued rotation of the ratchet in one direction, and means for operating the ratchet wheel comprising a pawl for connection to the line space plunger of the typewriting

machine and arranged to operate the ratchet through the space of one tooth upon each 40 reciprocation of the plunger.

3. An attachment for typewriters comprising a base portion adapted to be attached to the carriage of the typewriter, a signal mounted on said base, means for sounding 45 said signal at equal intervals upon completion of a predetermined number of lines of writing comprising a signal operating member for operating said signal upon each movement of a predetermined extent, a member 50 mounted for reciprocation on said base and adapted to operate said first mentioned member upon each such reciprocation, and means for connecting said member to the line space plunger of the typewriting machine to be operated thereby when the base portion is attached to the carriage of the machine.

4. In an attachment for typewriting machines, the combination of a base portion 60 rigidly attached to the carriage of said machine, a gong carried by said base, a striker for said gong, a ratchet mounted on said base for rotation in one direction only having means for operating said striker once in each revolution, a pawl for operating said ratchet, a reciprocating member mounted on said base and operating said pawl, said reciprocating member having means for attachment to the line space plunger of a 65 typewriting machine when the said base portion is attached to said machine.

In testimony whereof we affix our signatures.

JOHN J. HAGGERTY.
ERNEST D. VAN WIE.
